UNITED STATES PATENT OFFICE.

OTIS DIMOCK, OF NEW LONDON, CONNECTICUT.

ANVIL.

SPECIFICATION forming part of Letters Patent No. 281,847, dated July 24, 1883.

Application filed March 31, 1883. (No model.)

To all whom it may concern:

Be it known that I, OTIS DIMOCK, a citizen of the United States, residing at New London, in the county of New London and State of Connecticut, have invented certain new and useful Improvements in Anvils, of which the following is a specification, reference being had therein to the accompanying drawings.

My invention has relation to anvils; and its object is to provide a smith's anvil, especially adapted to straightening shafting and the like; and the novelty consists in the construction of the same, as will be hereinafter more fully described, and particularly pointed out in the claims.

In the accompanying drawings similar letters of reference indicate like parts of the invention.

Figure 1 is a perspective elevation of my improved anvil, and Fig. 2 a similar view with anvil-block elevated.

A is the base, and may be of any suitable size and shape. The sides of this base are provided with ears or guides B B, and between said guides is a straight semicircular groove, C, in which is placed a shaft, E. In the face of the base, on either side of the groove C, are two vertical holes, d d, which form seats for the springs D D, and are of a sufficient depth 30 to admit of the springs being compressed into them, or flush with the face of the base A.

G is the anvil-block proper, and its under side is provided with a groove, F, corresponding to the groove C in the face of the base, so 35 that the block may be placed on the base between the guides B B, the groove F fitting over the shaft E; and it is retained in this position by the shaft and guides, while the springs

D D balance it on either side of the shaft, and at the same time allow it to tilt to either side 40 if pressure should be applied to the block on either side of the center of the shaft E. The face of the block is provided with a recess, H, and when a shaft is laid across the block at a right angle to the recess H and struck with a 45 sledge or hammer, the recess H allows the shaft to give at that point, while the balanced position of the block on the base admits of its adjustability to conform to the position of the shaft.

It will thus be seen that one man can readily handle a shaft that is "out of true," and with ease and facility readily "true it up," and ordinarily this would require the assistance of at least two men.

Having thus fully described my invention, what I claim as new and useful, and desire to secure by Letters Patent of the United States, is—

1. The base A, having groove C and shaft E, 60 in combination with the block G, having groove F, substantially as set forth.

2. The base A, having groove C, shaft E, and springs D D, in combination with the anvil-block G, having groove F, substantially 65 as set forth.

3. The base A, having groove C, shaft E, springs D D, and guides B B, in combination with the anvil-block G, having groove F and recess H, substantially as shown and described. 70

In testimony whereof I affix my signature in presence of two witnesses.

OTIS DIMOCK.
